WIRE TERMINAL LOOP FORMER

C. Lawrence Sherman, Cherry Valley, Ill., assignor
of one-half to Joe E. Tabor, Belvidere, Ill.

Application February 12, 1945, Serial No. 577,407

18 Claims. (Cl. 140—104)

1

This invention relates to a new and improved wire terminal loop former.

Electricians have a real need for a practical form of tool of the kind mentioned, because of the time consumed otherwise in forming loops with make-shift means, and the fact that the loops formed in that way are not at all uniform in size or shape, and hence work done in that way does not present a good workmanlike appearance. It is, therefore, the principal object of my invention to provide a wire terminal loop former of a type somewhat resembling a pair of pliers, which is of a size and weight so that the workman can easily carry it in the pocket of his overalls to be accessible immediately whenever needed, and which is adapted to form a neat loop of the size desired merely by the closing of the handles of the tool after the stripped end of the wire on which the loop is to be formed has been properly inserted in the tool.

A salient feature of the present tool is the provision of a rotary die which is slidably mounted with respect to the frame of the tool for movement transversely with respect to the wire-gripping jaws in the commencement of the loop forming operation to make a reverse bend in the stripped end portion of the wire before the die is turned to form the loop, whereby the resulting loop has its center in line with the wire, instead of being in offset relation thereto. The one handle of the tool actuates the die, and the other handle actuates the movable gripping jaw.

The invention is illustrated in the accompanying drawing, in which:

Fig. 1 is a side view of a wire terminal loop former made in accordance with my invention, the die and handles being indicated in dotted lines in a moved position to illustrate the reverse bend feature;

Fig. 2 is a sectional view looking at the inside of the tool, the section being taken in a plane behind the cover plate, and

Figs. 3 and 4 are views showing a wire before and after the forming of the loop.

The same reference numerals are applied to corresponding parts throughout the views.

The tool is shown substantially full size in Fig. 1, and comprises a hollow head or frame member 5 of channel cross-section onto which a cover plate 6 is fastened by the nuts 7, 8 and 9 that thread on the projecting bolts 10, 11 and 12, respectively. These bolts pass freely through holes provided in the cover plate, and the bolts 10 and 11 provide pivots for the handles 13 and 14. The cover plate 6 has an outwardly project-

2

ing lug provided thereon, as indicated at 15, constituting a stationary wire-gripping jaw, the shoulder 16 on the inner end of which serves as a stop for engagement by the insulation 17 on the wire 18 when the stripped end 19 of the wire is inserted in the tool, as shown in Fig. 1. 20 is a movable wire-gripping jaw provided on the upper end of a slide 21 which works in a vertical guideway 22 provided in the narrower upper end portion 23 of the frame member 5. The handles 13 and 14 are pivoted in the opposite sides of the wider lower end portion 24 of the frame member 5, and the handle 14 has a lug 25 which projects inwardly and fits freely in a slot 26 provided therefor in the lower end portion of the slide 21 to provide an operating connection between the handle 14 and the slide, so that the jaw 20 is moved upwardly toward the jaw 15 to grip the insulated portion 17 of the wire 18 when the handles 13 and 14 are closed between the thumb and fingers of one hand. The cover plate 6 is cut away below the jaw 15, as indicated at 27, to provide operating clearance for the movable jaw 20, and a grasshopper type spring 28, which is coiled around the bolt 11 and has a stationary end 29 abutting the inside of the frame member 5 and a movable end 30 looped around the projection 31 on the handle 14, serves normally to hold the jaw 20 in a retracted position and returns the jaw to that position after it has been operated by the closing of the handles just as soon as the handles are released.

The handle 13 also has a grasshopper type spring 32 cooperating therewith, the fixed end 33 of which has abutment with the inside of the frame member 5, as shown in Fig. 2, and the movable end 34 of which is looped around a projection 35 on the handle, whereby normally to hold the handle 13 in the full-line position shown in Fig. 1. A lug 36 projecting from the pivoted end of the handle 13 has its outer end entered freely in a notch 37 in the lower end of a rack 38. This rack is reciprocable in a guideway 39, one side of which is provided in the frame member 5, and the other side of which is provided in a slide 40 that is guided for reciprocatory movement in the narrower upper end portion 23 of the frame member between the stop 41 and the bolt 12. A cylindrical die 42 is pivotally mounted on the slide 40, and has a pinion 43 suitably fixed to turn therewith meshing with the rack 38. A pin 44 projects from the center of the die 42, and another pin 45 is provided on the die in radially spaced parallel relation to the pin 44,

these two pins cooperating, as will soon appear, to form the loop 46 in the wire (see Fig. 4). Notice that the center of the loop 46 falls on the center line $x-y$ of the wire 18. This is by virtue of the reverse bend 47, the forming of which is illustrated in dotted lines in Fig. 1. Without this reverse bend, it is obvious that the loop would be in offset relation to the wire. The reverse bend is formed in the initial closing movement of the handle 13 when the stripped end 19 of the wire, by reason of its lying between the pins 44 and 45, resists turning of the die 42, as a result of which the die is given lineal movement with the slide 40 and rack 38 to the extent indicated in dotted lines in Fig. 1, thereby making the bend at 47. At the limit of lineal movement, that is to say when the slide 40 reaches the bolt 12, the rack 38, in the further closing movement of the handle 13, turns the die 42 by means of the pinion 43, and in this rotary movement of the die the pin 45, moving clockwise around the pin 44, bends the wire into the loop 46. A gauge plate 48, projecting from the frame member 5 on the opposite side from the wire-gripping jaws 15 and 20, indicates to the operator the proper length for the stripped end portion 19 to form the loop 46, so that the operator will not provide too much wire for this purpose. On the other hand, the operator may provide a shorter length of stripped end portion 19 whenever he desires to form a hook instead of a complete loop, as, for example, when it is desired to make a hook-on connection and avoid the necessity for removing a nut from a terminal. The gauge plate 48 is indicated as removably secured to the frame member 5 by a screw 49, so that a different gauge plate for a shorter or longer length of stripped end portion 19 may be fastened onto the tool. A leaf-spring 50 is preferably provided acting between the upper end of the frame member 5 and the slide 40 to return the latter to the stop 41 when the handle 13 is released, whereby also to return the die 42 to the starting position automatically. It is, of course, apparent that a number of different dies may also be provided interchangeable with the die 42 to enable forming loops of different diameters, such dies having center pins 44 of different radii and having the pins 45 differently spaced radially from the center pins to meet the different requirements. An oblong hole 50' is provided in the cover plate next to the jaw 15 to expose the die 42 and provide operating clearance therefor for its lineal movement.

The operation of the tool is believed to be clear from the foregoing description.

It is believed the foregoing description conveys a good understanding of the objects and advantages of my invention. The appended claims have been drawn to cover all legitimate modifications and adaptations.

I claim:

1. In a hand-operable wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith to wire gripping position in the closing movement of said handle, a die rotatable on said frame adjacent the jaws having a center pin and another pin projecting therefrom in radially spaced relation to the center pin to bend wire

around the center pin in the rotation of the die, and means operatively connecting the rotary die with the other handle for wire bending rotation in the closing movement of said handle.

5. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

10. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

15. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

20. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

25. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

30. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

35. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

40. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

45. In a wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith, a die rotatable on said frame adjacent the jaws having a center pin and another pin projecting therefrom in radially spaced relation to the center pin to bend wire around the center pin in the rotation of the die, means operatively connecting the rotary die with the other handle for rotation in the movement thereof, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

4. In a wire-bending device, the combination of a frame, wire-gripping means thereon, a rotary die, means slidable on the frame transversely with respect to the wire gripped by said gripping means rotatably supporting said die, a center pin projecting from said die and companion pin on said die in radially spaced substantially parallel relation to the center pin between which the wire to be formed into a loop is adapted to be extended from the gripping means, a pair of operating handles adapted to be moved relative to said frame to opened or closed position, and means operable by said handles in their closing movement for giving the slide lineal movement to said frame to a predetermined extent and the die rotary movement through a predetermined angularity.

5. In a wire bending device, the combination of a frame, wire-gripping means thereon, a rotary die, means slidable on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pair of operating handles adapted to be moved relative to said frame to opened or closed position, and means operable by said handles in their closing movement for giving the slide lineal movement to said frame to a predetermined extent and the die rotary movement through a predetermined angularity.

6. In a wire bending device, the combination of a frame, wire-gripping means thereon, a rotary die, means slidable on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pair of operating handles adapted to be moved relative to said frame to opened or closed position, and means operable by said handles in their closing movement for giving the slide lineal movement to said frame to a predetermined extent and the die rotary movement through a predetermined angularity.

7. In a wire bending device, the combination of a frame, wire-gripping means thereon, a rotary die, means slidable on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pair of operating handles adapted to be moved relative to said frame to opened or closed position, and means operable by said handles in their closing movement for giving the slide lineal movement to said frame to a predetermined extent and the die rotary movement through a predetermined angularity.

predetermined extent and the die rotary movement through a predetermined angularity, a stop on said wire-gripping means for engagement by the end of the insulated portion of an electric wire, and a gauge on said frame on the opposite side of said die from said gripping means and in a predetermined spaced relation thereto for indicating the length of stripped wire required to form a loop.

6. A wire terminal loop former, comprising a hollow frame member having a relatively narrow upper end portion and a relatively wide lower end portion, handles pivotally mounted in the opposite sides of the wider lower end portion of said frame member, spring means normally spreading said handles apart, a fixed jaw on the narrow upper end portion of said frame member, a movable jaw spaced therefrom carried on a slide guided in the narrow upper end portion of said frame member, means operatively connecting the lower end of said slide with the adjacent one of said handles for reciprocatory movement in the oscillation thereof, another slide guided for reciprocatory movement in the narrow upper end portion of said frame member in a direction transversely relative to a wire gripped between said jaws, a die rotatably mounted on the latter slide carrying a center pin and another pin in radially spaced relation to the center pin, a rack and pinion for transmitting reciprocatory and rotary movement to said die, and means operatively connecting the rack with the other of said handles for reciprocation of the rack in the oscillatory movement of the handle.

7. A device as set forth in claim 6, wherein one of said jaws has a shoulder provided thereon for abutment with the end of the insulation on an electric wire when inserted between said jaws, and a gauge projecting from the narrow upper end portion of said frame member on the opposite side of the die from said jaws, having a portion spaced a predetermined distance from said jaws to indicate the length of stripped wire required to form a loop.

8. A device as set forth in claim 6, including spring means acting between the outer end of said narrow upper end portion and said die-carrying slide, tending to move the latter to retracted position.

9. In a hand-operable wire-bending tool, the combination of a frame, a pair of handles pivoted relative to said frame, a pair of wire-gripping jaws, one of which is provided on the frame and the other of which is movable with respect thereto, means operatively connecting the movable jaw with one of said handles for movement therewith to wire gripping position in the closing movement of said handle, a die rotatable on said frame adjacent the jaws having a center pin and another pin projecting therefrom in radially spaced relation to the center pin to bend wire around the center pin in the rotation of the die, a slide supporting said die for lineal movement transversely with respect to a wire gripped in said jaws, means limiting such lineal movement, means operatively connecting said slide and die with the other handle for lineal movement jointly and rotary movement of the die alone thereafter in the closing movement of the handles, and spring means for normally returning said slide to retracted position.

10. In a wire-bending device, the combination of a frame, wire-gripping means thereon, a rotary die, means slidable on the frame transversely

with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pair of operating handles adapted to be moved relative to said frame to opened or closed position, means operable by said handles in their closing movement for giving the slide lineal movement and the die rotary movement, and spring means for normally returning said slide to retracted position.

11. In a wire-bending tool, the combination of a frame, a pair of handles pivoted relative to said frame, a pair of wire-gripping jaws operable by closing the handles, a die rotatable on said frame adjacent the jaws having a center pin and another pin projecting therefrom in radially spaced relation to the center pin to bend wire around the center pin in the rotation of the die, said die being also operable by closing the handles, one of said jaws having a shoulder provided thereon for abutment by the end of the insulated portion of an electric wire preliminary to the gripping of said insulated portion, and a gauge projecting from said frame on the opposite side of said die from said jaws and at a predetermined distance therefrom for indicating the length of stripped wire required to form a loop.

12. In a wire-bending tool, the combination of a frame, a pair of handles pivoted relative to said frame, a pair of wire-gripping jaws operable by closing the handles, a die rotatable on said frame adjacent the jaws having a center pin and another pin projecting therefrom in radially spaced relation to the center pin to bend wire around the center pin in the rotation of the die, a slide supporting said die for lineal movement transversely with respect to a wire gripped in said jaws, and means limiting such lineal movement, said slide and die being also operable by closing said handles and being arranged to have lineal movement jointly and rotary movement of the die alone thereafter in the closing movement of said handles.

13. A wire terminal loop former, comprising a hollow frame member having a relatively narrow upper end portion and a relatively wide lower end portion, handles pivotally mounted in the opposite sides of the wider lower end portion of said frame member, spring means normally spreading said handles apart, a fixed jaw on the narrow upper end portion of said frame member, a movable jaw spaced therefrom carried on a slide guided in the narrow upper end portion of said frame member, another slide guided for reciprocatory movement in the narrow upper end portion of said frame member in a direction transversely relative to a wire gripped between said jaws, a die rotatably mounted on the latter slide carrying a center pin and another pin in radially spaced relation to the center pin, a rack and pinion for transmitting reciprocatory and rotary movement to said die, and means operatively connecting the rack and first slide with said handles for reciprocation in the closing movement of the handles.

14. A device as set forth in claim 13, wherein one of said jaws has a shoulder provided thereon for abutment with the end of the insulation on an electric wire when inserted between said jaws, and a gauge projecting from the narrow upper end portion of said frame member on the opposite

side of the die from said jaws, having a portion spaced a predetermined distance from said jaws to indicate the length of stripped wire required to form a loop.

15. A device as set forth in claim 13, including spring means acting between the outer end of said narrow upper end portion and said die-carrying slide, tending to move the latter to retracted position.

16. In a wire-bending device, the combination of a frame, wire-gripping means thereon, a rotary die, a slide slidable to a predetermined limited extent on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pinion for turning said die, and a rack meshing with said pinion and reciprocable relative to said slide so as to transmit lineal movement to the slide to its limit position and thereafter turn the die through a predetermined angularity.

17. In a wire-bending device, the combination of a frame, wire-gripping means thereon, a rotary die, a slide slidable to a predetermined limited extent on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pinion for turning said die, a rack meshing with said pinion and reciprocable relative to said slide so as to transmit lineal movement to the slide to its limit position and thereafter turn the die through a pre-

5 determined angularity, a stop on said wire-gripping means for engagement by the end of the insulated portion of an electric wire, and a gauge on said frame on the opposite side of said die from said gripping means and in a predetermined spaced relation thereto for indicating the length of stripped wire required to form a loop.

10 18. In a wire-bending device, the combination of a frame, wire-gripping means thereon, a rotary die, a slide slidable to a predetermined limited extent on the frame transversely with respect to the wire gripped by said gripping means rotatably supporting said die, a center pin projecting from said die and a companion pin on said die in radially spaced substantially parallel relation to the center pin between which the wire to be formed into a loop is adapted to be extended from the gripping means, a pinion for turning said die, a rack meshing with said pinion and reciprocable relative to said slide so as to transmit lineal movement to the slide to its limit position and thereafter turn the die through a predetermined angularity, and spring means 15 for normally returning said slide to a retracted position.
